UNITED STATES PATENT OFFICE.

EDWARD THOMPSON DIDEN, OF PINE BLUFF, ARKANSAS.

LOCOMOTIVE VALVE GEAR.

1,404,936. (U.S. 1,404,936)

Specification of Letters Patent. Patented Jan. 31, 1922.

Application filed January 30, 1918. Serial No. 214,502.

To all whom it may concern:

Be it known that I, EDWARD THOMPSON DIDEN, a citizen of the United States, residing at Pine Bluff, in the county of Jefferson and State of Arkansas, have invented a new and useful Locomotive Valve Gear, of which the following is a specification.

It is the object of this invention to provide a locomotive valve gear wherein eccentricities are dispensed with, the mechanism substituted for the eccentricities being mounted in an accessible position on the outside of the wheel, a quick valve travel being secured, and a fixed lead at any travel of the valve being obtained.

A typical embodiment, merely, of the invention, is shown in the drawings, and, within the scope of what is claimed, changes such as a mechanic might make, may be resorted to without departing from the spirit of the invention.

In the drawings:—Figure 1 shows the valve gear in side elevation, parts being sectioned; Figure 2 is a top plan wherein parts are broken away; and Figure 3 is an elevation of the crank.

The numeral 1 marks a drive wheel carried by an axle 3 and having a reinforcement 2 in which is mounted a pin 4, disposed eccentrically on the wheel. The invention includes a crank comprising a first part 5, the outer end of which is secured rigidly at 6 to the pin 4, the crank comprising a second part 7 disposed at an acute angle to the part 5 and carrying a connection 8 rigidly secured at 9 to the inner end of the part 5 of the crank. The outer end of the part 7 of the crank is supplied with a wrist pin 10.

A main rod 11 is pivoted on the pin 10 and a main rod 12 is pivoted on the connection 8. Rock arms 14 and 15 are fulcrumed intermediate their ends on a suitable support 16. The rod 11 is pivoted at 17 to the lower end of the rock arm 14 and the rod 12 is similarly pivoted to the lower end of the rock arm 15.

At 18 there appears a link to which an auxiliary rod 19 is pivoted at 20, an auxiliary rod 21 being pivoted at 32 to the link 18, the pivotal connections 20 and 32 being spaced apart. As shown at 22, the rod 19 is pivoted to the upper end of the rock arm 14, the rod 21 being pivoted at 23

to the upper end of the rock arm 15. Brackets 24 are secured to the link 18 between the pivot elements 32 and 20 and carry outstanding trunnions 25 connected with a raising and lowering device 26 which need not be described in detail, since this part of the invention may be constructed as desired. The link 18 slides on a block 27, for adjustment, the block being pivoted in a recess 28 formed in an actuating member 29 connected with a slide valve 30 cooperating with a valve chest 31.

The link 18 is raised and lowered by the mechanism 26 to secure a reversal, in the well known manner. The rods 11 and 12, being actuated by the crank mechanism, tilt the rock arms 14—15, motion being imparted to the valve 30 by the rods 21 and 19, the link 18 and the actuating member 29. The rock arms 14—16 are used to maintain a fixed lead on the valve 30 and this result would not be obtained if the rods 11—12 were coupled directly to the link 18, but since the rods 11—12 are pivoted to the lower ends of the rock arms, the link 18, when raised or lowered, will move on a radius with the pivotal connections 22 as centers, the link radius being drawn from the points 22 and not from the center of the main axle 3. The crank construction 5—7 affords a substitute for eccentricities, and permits the mechanism which is effective initially to actuate the valve 30, to be located in an accessible position on the outside of the wheel.

I claim:—

In a device of the class described, a drive wheel; a pin carried by the wheel adjacent to the periphery; a crank comprising first and second parts disposed at an acute angle to each other, the outer end of the first part being secured rigidly to the pin; a connection rigidly secured to the first part of the crank; a wrist pin mounted on the outer end of the second part of the crank; main rods one of which is pivoted at its rear end on the pin, the other of which is pivoted at its rear end on the connection; rock arms and means for fulcruming the same intermediate their ends, the main rods being pivoted, each, at its forward end, to the lower end of one rock arm; auxiliary rods each pivoted at its rear end to the upper end of one rock arm;

a link whereunto the forward ends of the auxiliary arms are pivoted in spaced relation to each other; a slide valve; an actuating member connected to the valve and having a recess; a block pivoted in the recess and carrying the said actuating member slidably; and means under the control of an operator for sliding the link on the block.

In testimony that I claim the foregoing as my own, I have hereto affixed my signature in the presence of two witnesses.

EDWARD THOMPSON DIDEN.
